Primary Examiner — Patricia A Palasik(74) *Attorney, Agent, or Firm* — Sarika Singh; Mcneely, Hare & War LLP(57) **CLAIM**

The ornamental design for an electric welding machine shell, as shown and described.

DESCRIPTION

FIG. 1 is a perspective view of an electric welding machine shell showing my new design;

FIG. 2 is an upside-down perspective view thereof;

FIG. 3 is a right view thereof;

FIG. 4 is a left view thereof;

FIG. 5 is a front view thereof;

FIG. 6 is a back view thereof;

FIG. 7 is a top view thereof; and,

FIG. 8 is a bottom view thereof.

The broken lines in the figures show control knobs that depict unclaimed environmental subject matter.

1 Claim, 8 Drawing Sheets(56)
